(57) **CLAIM**

The ornamental design for a battery powered toy horseshoe magnet, as shown and described.

DESCRIPTION

FIG. 1 is a perspective view of the battery powered toy horseshoe magnet design of the present invention.

FIG. 2 is a left side view of the horseshoe magnet.

FIG. 3 is a right side view of the horseshoe magnet.

FIG. 4 is a front of the horseshoe magnet.

FIG. 5 is a rear view of the horseshoe magnet.

FIG. 6 is a top view of the horseshoe magnet; and,

FIG. 7 is a bottom side view of the horseshoe magnet.
